(57) **CLAIM**

The ornamental design for a floor rocker, as shown and described.

DESCRIPTION

FIG. 1 is a right front perspective view of a floor rocker showing our new design;

FIG. 2 is a front view thereof;

FIG. 3 is a right side view thereof;

FIG. 4 is a left side view thereof;

FIG. 5 is a rear view thereof; and,

FIG. 6 is a top view thereof.

The contoured seat and seatback surfaces in FIGS. 1-6 are stippled to indicate fabric.

The dot-dash lines in the figures are boundary lines and form no part of the claimed design.
